UNITED STATES PATENT OFFICE.

LOUIS A. PIAGET, OF PATERSON, NEW JERSEY.

DESIGN FOR A PICKLE-FORK.

SPECIFICATION forming part of Design No. 23,860, dated December 11, 1894.

Application filed October 15, 1894. Serial No. 525,992. Term of patent 3½ years.

To all whom it may concern:

Be it known that I, LOUIS A. PIAGET, a citizen of the United States, residing at Paterson, in the county of Passaic and State of New Jersey, have invented and produced a new and original Design for Pickle-Forks, of which the following is a specification, reference being had to the accompanying drawing, forming part thereof.

The drawing clearly shows my new design, —A— indicating the handle; —B—, the bowl; —C—, the sides of bowl up-turned; —D—, the tines of the fork being turned over as indicated by —D'—, the central tine of the fork not being turned up as the other tines but left extended and having an arrow shaped point as indicated by —E—.

The bottom of the bowl —B— is provided

with open figured work as shown in the drawing.

The leading features of my design consist in the handle —A— and bowl portion —B—, the bowl portion —B— having the sides turned up, and the bottom provided with open figured work, and all of the tines except the central one being turned over, the central tine being extended and provided with an arrow head as herein shown and described.

I claim—

The design for a pickle fork, as herein shown and described.

LOUIS A. PIAGET.
